UNITED STATES PATENT OFFICE.

OTTO A. HEPPE, OF LA GRANGE, ILLINOIS.

ROLL AND PACKAGE

1,380,475.

Specification of Letters Patent. Patented June 7, 1921.

Application filed September 6, 1918. Serial No. 252,839.

To all whom it may concern:

Be it known that I, OTTO A. HEPPE, a citizen of the United States, residing at La Grange, in the county of Cook and State of Illinois, have invented certain new and useful Improvements in Rolls and Packages, of which the following is a specification.

My invention relates to containers for cartons.

10 One of the objects of my invention is to provide a convenient and inexpensive receptacle for containing and retaining one or more cartons or containers within a cylindrical roll of sheet material.

15 Another object is to provide a combined roll and package, wherein the package is retained within the roll but may be removed without injury to the roll or package.

Asphaltic roofing material, when furnished in long relatively narrow sheets is usually rolled into cylindrical form, with an axial opening about three inches in diameter and the ultimate diameter approximately 10 or 12 inches.

25 In the axial opening a carton containing a suitable cement for joining the overlapping sheets together, and another carton containing suitable nails for attaching the sheets to the underlying roof support are usually inserted within the opening in the roll and then closures or heads, are placed over each end of the roll to close the cylinder, so as to retain the cartons therein.

Owing to the character of the roll, it is a 35 matter of some difficulty and expense to construct and apply appropriate closures, or heads, that will remain in place under the ordinary rough usage to which the roll is subjected in transit.

40 The axial shifting of the cartons, when the roll is inverted, causes severe bombardment of the lower head or closure, thereby frequently disengaging it from the roll and permitting the cartons to be dropped and 45 lost out of the receptacle within which they were contained.

In carrying my invention into effect I provide a package or carton retaining means for holding the cartons inside of the cylinder, made, preferably, of an attached part 50 of the rolled sheet and place the cartons, end to end, within the first convolution of the convolved cylinder, thereby utilizing the holding effect by friction between the inter-related parts, due to the accumulated ten-

sion of the successive convolutions as the strip is wound into a roll. By providing a carton retainer within the opening of the roll, heads or closures for the roll ends become unnecessary.

60 In the accompanying drawing forming a part hereof,

Figure 1 is a fragmentary perspective view of one end of an elongated sheet to be wound into a roll, showing the cartons in 65 place, before rolling the sheet into cylinder form.

Fig. 2 is a similar perspective view showing a slashed part of one end of the sheet to form integral strips folded over the ends of 70 the cartons to provide heads for the carton retainer.

Fig. 3 is an enlarged longitudinal central section of the mid part of the roll, taken on line 3—3 of Fig. 4 showing the manner of 75 retaining the cartons in the roll.

Fig. 4 is a transverse section, taken on line 4—4 of Fig. 3, showing one of the heads of the carton retainer made from the slashed part of the sheet.

80 In all views the same reference characters are employed to indicate similar parts.

5 represents a sheet of material, such as that usually employed for roofing, consisting of a flexible, asphalt-treated base, of 85 relatively long dimensions and of narrow proportion, to be wound into a roll. The material is made in long continuous sheets, from which a portion, to constitute a roll, is cut. When the portion 5 is cut from the 90 roll stock, at the end 6, it is also slashed, as at 7, and 8, to points 9 and 10. The slashed parts, 11 and 12, which form the retainer, are preferably about as wide as the diameter of the cartons 13 and 14, or of less width. 95 Before the sheet 5 is rolled into successive convolutions, as shown in Figs. 3 and 4, the strip 12 is passed over one end and upper side of the package composed of cartons 13 and 14 to form the head 15 and the other 100 strip 11 is folded over the package in the same manner and over the confronting surface of the end 12, to form head 16, as clearly shown in Fig. 2, after which the sheet 5 is rolled into cylinder form, as shown 105 in Figs. 3 and 4. The overlying convolutions of the sheet tightly hold and bind the parts 11 and 12 in contact with each other and with the surrounding portions of the sheet and firmly retain the cartons inside the 110

opening within the roll. The strips may therefore be integral with the sheet, as shown, or separated therefrom.

When the sheet 5 is unrolled for use and 5 the cartons removed, the parts 11 and 12 may then be severed on lines 7 and 8 and removed from the sheet and the sheet used in the usual manner.

When the cartons are contained in a receptacle, constructed in the manner described, 10 they cannot shift axially to a material extent, and furthermore they are positively held against such movement by the heads 15 and 16. Therefore it would be difficult 15 to remove them from the roll until the sheet 5 is unrolled and laid out flat, as shown in Figs. 1 and 2.

While I have shown the strips 11 and 12 to be inseparable parts of the relatively large 20 sheet 5, it is, of course, within the contemplation of my invention to provide a separate part for this purpose and either secure it directly to the sheet 5 or depend upon the frictional engagement of the parts to hold 25 the container within the roll.

While I have herein shown a single embodiment of my invention, for the purpose of clear disclosure, it will become apparent, to persons skilled in the art, that changes 30 may be made in the general arrangement and configuration of the parts, within the scope of the appended claims.

Having described my invention, what I claim is:—

35 1. In combination with a convolved roll of sheet material having an axial opening; a carton container therein comprising an unsegregated strip attached to one end of the sheet, of a width not greater than the 40 diameter of the carton, extending over the ends and sides of the carton, or cartons and in engagement with the inner convolution of the roll.

45 2. A carton container formed of a roll of sheet material, having a retaining member overlapping an end of the carton, said retaining member being an integral part of

the sheet material and coöperating with the wall of the central opening of the roll to hold the carton in place within the opening. 50

3. A carton container comprising a sheet of material formed into a roll with a central opening for a carton, and a retaining member formed as a strip from the sheet of material and overlapping an end of the carton and coöperating with the wall of the opening in the roll to hold the carton in place. 55

4. In combination with an elongated sheet of roofing material rolled into a series of convolutions to form a plural wall cylinder; a carton therein and integral parts of the sheet folded over the ends and one side of the carton and held in place by frictional engagement with said convolutions. 60

65 5. A carton container comprising a sheet of material formed into a multi-convolution roll with a central opening, and a retaining member comprising a strip for overlapping an end of a carton within the opening and being held in place by frictional engagement with the wall of the opening in the roll. 70

75 6. A carton container comprising a sheet of material formed into a roll with a central opening, and a pair of strips formed from the sheet material and overlapping the ends of a carton located within the opening, the ends of said strips overlapping each other and being held in place by frictional engagement with the wall of the opening in 80 the roll.

8. A combined roll comprising an interior package and a sheet wound around the same, said sheet having a strip extending inward from one edge and folded over said package 85 for confining the same.

8. The article claimed generally in claim 7 hereof, wherein two strips are formed extending inwardly from opposite sides of the sheet and are folded over to confine the 90 package within the roll.

In testimony whereof I hereunto subscribed my name.

OTTO A. HEPPEs.
